UNITED STATES PATENT OFFICE.

LEIGH W. HOSTETTLER, OF TARENTUM, PENNSYLVANIA, ASSIGNOR TO ALLEGHENY STEEL COMPANY, A CORPORATION OF PENNSYLVANIA.

JOURNAL-BOX LID.

1,425,093.

Specification of Letters Patent. Patented Aug. 8, 1922.

Application filed November 22, 1920. Serial No. 425,637.

To all whom it may concern:

Be it known that I, LEIGH W. HOSTETTLER, a citizen of the United States, and a resident of Tarentum, in the county of Allegheny and State of Pennsylvania, have made a new and useful Improvement in Journal-Box Lids, of which the following is a specification.

My invention relates to railway-car journal boxes, and consists in novel means for retaining the hinge pin of the box lid.

The object of my invention is to avoid the use of the usual bolts and cotters. The vibrations of the usual spring cotter in its slot frequently causes the cotter to crystallize, break and fall, thus permitting the bolt to be jarred through the lid and box and drop out, releasing the lid with attending damage to the journal. Workmen, through accident or carelessness, occasionally fail to provide the hinge pin with its cotter and either leave the pin free to work out, or substitute a makeshift which is not as satisfactory as the cotter. My device eliminates these objectionable results of present lid-secur ing means.

In the accompanying drawings, Figure 1 is a front elevation of a journal box equipped with my improved lid; Fig. 2 is a horizontal section on line 2—2 of Fig. 1, and Fig. 3 is a side elevation of the box shown in Fig. 1.

The journal box 1 is of any familiar type and mounts an axle 2 in the ordinary manner. The journal-box lid 3 is preferably a steel stamping and has an upper central portion 4 shaped to contain the usual spring (not shown) which keeps the lid closed. Upper side portions 5 are bent to form cylindrical bearings for the hinge pin 6.

The outer end of each portion 5 is provided with a lug or ear 7 adapted to extend outwardly, as shown at 8, to permit the insertion of the hinge pin 6, or to be bent inwardly at right angles, as shown in full lines, to retain the hinge pin.

It will be noted that the hinge pin is simply a piece of round iron rod of the requisite length. It has no head formed thereon or any hole for a spring cotter or other retaining key. The absence of machining and

the shorter length materially reduce the cost of the hinge pin. The absence of a spring cotter eliminates another item of expense. The addition of the ears 7 does not materially increase the cost of the lid. When this difference in cost is multiplied by the quantities of journal boxes in use on a single line, the economy to a railroad company is apparent.

I realize that the ear may be formed and positioned differently and I contemplate modifications in my improved lid without departure from the spirit of the invention disclosed.

I claim as my invention:

1. A journal-box lid provided with a cylindrical portion adapted to receive a hinge pin and having ears at the end thereof adapted to be bent over the ends of said cylindrical portion to retain a hinge pin within same.

2. A hinge comprising a plurality of co-operating members provided with eye portions adapted to receive a hinge pin and an ear portion carried by one of said eye portions adapted to be bent over the end of said pin and to a position flat against the same to retain said pin against displacement.

3. A hinge comprising a plurality of co-operating hinge members provided with co-acting eye portions adapted to receive a hinge pin and an extension formed on one of said eye portions adapted to be bent over the end of said pin and into a plane transverse to the axis thereof to retain said pin against displacement.

4. A hinge comprising a plurality of co-operating hinge members provided with co-acting eye portions, a hinge pin disposed within said eye portions and terminating flush with the outer edges thereof and ear portions carried by said eye portions adapted to be bent flat against the extremities of said pin to partially close said eye to prevent the displacement of said pin therefrom.

In testimony whereof, I have hereunto subscribed my name this 31st day of October, 1920.

LEIGH W. HOSTETTLER.
